APPARATUS FOR AUTOMATICALLY FILLING WELL CONDUITS WITH FLUID

John F. Muse, Montebello, Calif., assignor to Baker Oil Tools, Inc., Vernon, Calif., a corporation of California

Application April 27, 1953, Serial No. 351,396

20 Claims. (Cl. 166—225)

The present invention relates to subsurface well apparatus, and more particularly to apparatus for controllably filling a conduit string, such as well casing or drill pipe, with fluid as the string is being lowered in a well bore.

An object of the present invention is to provide improved apparatus for automatically controlling the rate at which fluid in the well bore can flow into the conduit string in which the apparatus is embodied.

A further object of the invention is to provide apparatus which automatically reduces flow of fluid in the conduit string disposed in the well bore when the velocity of flow therein tends to increase, and which increases the flow of fluid as its velocity tends to decrease. In a more limited sense, the apparatus provides a substantially constant flow of fluid in the conduit string.

Another object of the invention is to provide an apparatus adapted to be incorporated in a conduit string to be disposed in a well bore, in which the apparatus embodies a back pressure valve to prevent upward flow of fluid in the conduit string, but in which provision is made to allow the conduit string to fill with fluid at a controlled rate as it is lowered in the well bore, the back pressure valve being operable to perform its function at all times.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Fig. 1 is a longitudinal section through an apparatus embodying the invention, disposed in a well bore and with the valve mechanism in open position;

Fig. 2 is an enlarged fragmentary section of part of the apparatus disclosed in Fig. 1;

Fig. 3 is a side elevational view of a locking member incorporated in the apparatus;

Fig. 4 is a view similar to Fig. 1, disclosing parts of the apparatus in another relative position;

Fig. 5 is a view similar to Fig. 1, disclosing the apparatus with certain parts in still another relative position.

As disclosed in the drawings, the apparatus A is embodied in a string of casing B disposed in a well bore C, the apparatus being specifically provided in the casing shoe of the casing string. It is to be understood, however, that the apparatus is also useful in other types of conduit strings, and that it can also be incorporated at intermediate points in the conduit string.

As specifically illustrated in the drawings, the apparatus includes an outer tubular member 10 having an upper threaded box 11 threadedly attached to the lower pin 12 of an adjacent casing section B, the casing sections being connected to one another and extending to the top of the well bore, in which the casing string is to be lowered.

2

The tubular member 10 has a cementitious plug 13 cast therein, this plug being inseparably united to the tubular member by providing longitudinally spaced circumferential grooves 14 in the tubular member in which cementitious material will flow during the casting operation to provide the locking plug ribs 15 in the grooves. The lower end 16 of the plug is rounded, to provide a guiding nose for facilitating passage of the casing string past restrictions or other obstructions encountered in the well bore during descent of the casing string therewithin.

An upwardly closing back pressure valve device 17 is incorporated in the apparatus to preclude return flow of fluid into the casing string B after it has been lowered to its desired depth in the well bore. The back pressure valve includes a valve housing 18 disposed in the lower portion of the cementitious plug and bearing against a clamp ring 19 that secures a seal ring 20 against a valve seat 21 thereabove. A valve member 22, which may be in the form of a ball, preferably buoyant in cement slurry, is disposed in the valve housing 18, being movable upwardly into engagement with the valve seat 21 and seal ring 20 to prevent upward flow of fluid through the seat. The ball is movable downwardly away from the seat 21 and into engagement with a plurality of circumferentially spaced lugs or fingers 23 between which the fluid can flow in moving through the casing shoe between its upper and lower ends.

Inasmuch as it is desired to have the casing string B fill automatically with the well bore fluid as it is lowered therewithin, a control mechanism for permitting such flow is disposed in the apparatus above the back pressure valve 17, since the latter will prevent upward flow of fluid through the lower portion of the shoe. This last-mentioned apparatus is designed to control the flow of fluid into the casing string, to prevent overflow of the fluid from the casing string at the top of the hole. As the flow of fluid tends to increase, the apparatus automatically throttles such flow. Conversely, as the flow of fluid into the casing string tends to decrease, then 40 the apparatus automatically opens to a fuller extent, to allow a greater quantity of fluid to flow into the conduit string. After the conduit or casing string has been lowered to the desired depth in the well bore, then means are provided for precluding ingress of fluid into the conduit string above the back pressure valve mechanism 17, in order that all fluid must then be moved down through the casing string for ejection through its lower end, the tendency of such fluid to flow back into the casing string being prevented by engagement of the ball valve member 22 with its companion seat 21.

As shown specifically in the drawings, the automatic valve mechanism for controlling the passage of fluid into the conduit string includes a composite housing 24 secured within the cementitious plug 13, as by providing longitudinally spaced peripheral grooves 25 on the housing, in which the cementitious material will flow during the casting operation to form locking ribs 26. This housing 24 includes a lower housing section 27 threaded into an intermediate housing section 28 having a plurality of radial ports 29 in alignment with companion ports 30 extending through the cementitious plug 13 and the tubular member 10. The intermediate housing section 28 is threadedly secured to the lower end of an upper housing section 31, which forms part of a guide to prevent rotation of a sleeve valve member 32 that is reciprocable within the housing 24. This sleeve valve member is elongate and has radial ports 33 therethrough, which are maintained in the same radial planes as the ports 29, 30 through the intermediate housing section 28, plug 13 and tubular member 10 by a pin and slot connection. As disclosed, such pin and slot connection includes a pin 34 threaded in a radial direction into the upper portion of

the sleeve valve member 32 and received within a companion longitudinal groove or slot 35 in the upper housing section 31.

When the sleeve ports 33 are aligned with the other ports 29, 30, fluid can flow between the exterior and interior of the casing shoe A, this fluid passing upwardly through a restricted passage or orifice 36 in the upper portion of the sleeve valve member 32 and into the casing section B thereabove, for continued upward flowing through the casing string. Leakage of fluid between the housing 24 and valve member 32 is precluded by the provision of an upper elastic seal ring 37 on one side of the housing ports 29 engaging the periphery of the sleeve valve 32 above its ports 33. This seal ring may be disposed in a housing groove 38 formed by the upper and intermediate housing sections 31, 28, between which the ring 37 is clamped. A similar lower seal ring 39, of rubber or rubber-like material, is disposed in a groove 40 formed between the intermediate housing section 28 and a clamp ring 41 below the housing ports 29. This clamp ring 41 is held in position by the upper end of the lower housing section 27.

The ports 33, 29, 30 will be in alignment when a stop and latch ring 42, disposed within a peripheral groove 43 in the sleeve valve 32, engages an inwardly and downwardly tapering shoulder 44 provided in the lower housing section 27. This stop and latch ring 42 is split and is capable of being forced inwardly within the groove 43 and into a position in which the periphery of the ring 42 has a diameter no greater than the inside diameter of the lower housing section 27, which will allow the entire sleeve 32 to move downwardly for the purpose of closing the ports through the housing 28, plug 13 and tubular member 10, this closing position being determined by the reception of the split latch ring 42 within a lock groove 45 in the housing 24 disposed a substantial distance below the shoulder 44. When the ring 42 enters this groove 45 in the manner described hereinbelow, then the sleeve ports 33 will be disposed below the lower non-metallic seal ring 39, preventing fluid communication between the sleeve ports 33 and the radial ports 29, 30 through the housing 28, cement plug 13 and tubular member 10.

As was stated above, the latch ring 42 has, as one of its functions, engagement with the tapered shoulder 44 to locate the sleeve ports 33 in alignment with the radial ports 29, 30. When in this position, the ports are in full communication with each other, allowing unimpeded flow of fluid to take place from the exterior of the tubular member 10 to the interior of the sleeve valve member 32. The sleeve valve 32 is urged in a downward direction toward the position just mentioned by a spring member, which is preferably in the form of a rubber or rubber-like tension sleeve 47, the upper end of the sleeve being secured to the lower portion of the sleeve valve member 32 by suitably clamping an enlarged upper end 48 thereof between the sleeve valve member 32 and a retainer ring 49 secured to the sleeve valve 32 in any suitable manner, as through use of the radial pins 50. The wall of the housing 24 prevents the retainer ring 49 from becoming dissembled from the sleeve 32.

In a similar fashion, the lower end 51 of the spring sleeve member 47 is of enlarged cross-section and is clamped between the lower portion of the housing section 27 and a retainer member 52 resting upon the upper end of the valve seat 21 and secured to the lower housing section by a plurality of radial pins 53. To equalize the fluid pressure on both sides of the rubber sleeve 47 it may be provided with a plurality of circumferentially spaced, longitudinally extending slots 54.

When the ports 33, 29, 30 are in fully aligned and completely opened position, with the ring 42 engaging the shoulder 44, the rubber spring sleeve member 47 may have no tension or slight tension therein. The upward movement of the sleeve valve member 32 within the housing 24 will stretch the rubber 47 and cause it to tend to

move the sleeve valve 32 downwardly to its initial position, as shown in Fig. 1 in which the ports are fully open. The upward movement of the sleeve valve 32 occurs under the action of the fluid flowing through the ports 33, 29, 30 and upwardly through the orifice 36 in the upper portion of the sleeve member. The fact that such fluid is throttled by the orifice passage 36 tends to build up a back pressure on the lower portion of the orifice, to move the sleeve valve 32 in an upward direction, thereby misaligning the sleeve valve ports 33 with respect to the other radial ports 29, 30 of the apparatus, and effecting a throttling of the fluid that can flow between the radial ports.

If fluid is flowing at a relatively low rate through the radial ports 29, 30, 33, very little back pressure would be built up within the sleeve 32 tending to elevate it. Accordingly, the sleeve valve 32 would be disposed in the fully open position disclosed in Fig. 1. In the event the velocity of the fluid passing through the radial ports 29, 30, 33, and upwardly through the orifice 36, increases substantially, then the back pressure built up in the sleeve 32 on the lower side of the orifice would elevate the sleeve valve to disalign the ports 33 and 29, 30, in the manner disclosed in Fig. 4, reducing the effective passage area between the housing ports 29 and the sleeve valve ports 33, and thereby throttling the flow at such points. Accordingly, it is evident that as the velocity of flow through the orifice 36 tends to increase, a greater throttling action occurs between the ports 33 and 29, through the longitudinal shifting of the sleeve valve member 32 in the housing 24 against the tension of the rubber spring sleeve 47. This throttling action maintains the volume of fluid passing through the orifice 36 at a substantially constant rate, since decrease in the velocity will cause the rubber spring 47 to pull the sleeve valve 32 back down to a position in which its radial ports 33 are more fully aligned with the radial ports 29, 30 in the housing 28, plug 13 and tubular member 10.

The rate at which fluid will flow into the conduit string B will depend upon the viscosity of the drilling mud, or other fluid in the well bore, the specific gravity of this fluid, the area of the orifice 36, and the force exerted by the rubber tension sleeve 47. The orifice diameter and the strength of the spring member or tension sleeve 47 may be selected, in dependence upon the specific gravity and viscosity of the fluid in the well bore, to insure a relatively slow flow rate of fluid into the conduit string, such that the fluid will not overflow at the top of the hole and drench the surface equipment and personnel.

The fluid will continue flowing into the apparatus during lowering of the conduit string B through the fluid in the well bore. When the conduit string or casing has reached the desired depth in the well bore, the fluid level within the casing will rise to approximate equality with the fluid level around the casing string. Thereafter, fluid may be pumped down the casing string B, the restricted orifice 36 causing a back pressure to build up above the sleeve valve member 32, overcoming the tension of the split latch ring 42, the tapered shoulder 44 forcing the latch ring 42 inwardly within the groove 43, whereupon the sleeve valve 32 can be shifted downwardly to the position disclosed in Fig. 5, in which the latch ring 42 will snap into the companion housing groove 45, precluding return of the sleeve to its initial position. When the sleeve 32 is locked in this downward position, its radial ports 33 will be disposed below the lower seal ring 39 in the housing 24, an imperforate portion of the sleeve valve being disposed in a closed position across the radial ports 29, 30 through the housing 28, plug 13 and tubular member 10. Accordingly, despite the relieving of the pressure in the casing string B, fluid can no longer pass between the exterior and the interior of the casing string through the radial ports 29, 30, 33.

The rubber spring member 47 may fold upon itself, in the manner disclosed in Fig. 5, when the sleeve valve

32 is pumped downwardly to the extent required, but the rubber sleeve valve 47 will not restrict the flow of fluid downwardly through the apparatus.

Circulating fluid, cement slurry, and the like, may now be pumped down the casing string B, shifting the ball valve member 22 downwardly from its seat 21, this fluid flowing around the ball valve member 22 and between the stop fingers 23 for discharge from the shoe A and for upward passage around the casing string B. When the pumping action is stopped and the fluid pressure in the casing string relieved, any tendency for fluid to flow back into the shoe A and the conduit string B will be precluded by the upward movement of the ball valve member 22 into engagement with its companion seat 21 and seal ring 20.

It is to be noted that the seal rings 37, 39 on opposite sides of the housing ports 29 slidably engage the periphery of the sleeve valve member 32, and that the latter member has the same external diameter at such points of slidable engagement. Accordingly, the pressure acting on the exterior of the sleeve valve member 32 is counterbalanced, so that the hydrostatic heads of fluid within and exteriorly of the apparatus do not tend to shift the sleeve valve member in either direction. It is merely the velocity of the fluid flowing through the orifice 36, and which builds up the back pressure on the underside of the orifice, which is effective to tend to elevate the sleeve valve 32 against the tension of the rubber spring member 47, and which determines the degree of throttling action caused by the misalignment of the ports 33 and 29, 30.

Although disclosed specifically in combination with a back pressure valve member 17, it is evident that the apparatus for controlling the flow of fluid into the conduit string B is effective in the absence of a back pressure valve mechanism, as, for example, by making the lower portion of the conduit string imperforate at the location of the back pressure valve apparatus. It is also evident that the apparatus is useful in general for controlling the flow of fluid into conduit strings, as, for example, in its use for production apparatus to automatically regulate the flow of well production into a tubing or similar conduit string positioned in the well bore.

The inventor claims:

1. In well apparatus: tubular means adapted to be incorporated in a conduit string to be lowered in a well bore; a back pressure valve in said tubular means adapted to close in an upward direction; said tubular means having a port through its side wall above said back pressure valve; a valve member in said tubular means having a passage therethrough in fluid communication with said back pressure valve and movable with respect to said port to regulate the flow of fluid therethrough, said valve member having a flow restricting passage through which fluid flowing through said port and into said valve member passes to build up a back pressure tending to elevate said valve member to restrict fluid flow through said port; said valve member being movable downwardly to a position closing said port.

2. In well apparatus: tubular means adapted to be incorporated in a conduit string to be lowered in a well bore; a back pressure valve in said tubular means adapted to close in an upward direction; said tubular means having a port through its side wall above said back pressure valve; a valve member in said tubular means having a passage therethrough in fluid communication with said back pressure valve and movable with respect to said port to regulate the flow of fluid therethrough, said valve member having a flow restricting passage through which fluid flowing through said port and into said valve member passes to build up a back pressure tending to elevate said valve member to restrict fluid flow through said port; said valve member being movable downwardly to a position closing said port, and spring means acting on said

valve member to urge it to a position allowing greater flow of fluid through said port.

3. In well apparatus: tubular means adapted to be incorporated in a conduit string to be lowered in a well bore; a back pressure valve in said tubular means adapted to close in an upward direction; said tubular means having a port through its side wall above said back pressure valve; a valve member in said tubular means having a passage therethrough in fluid communication with said back pressure valve and movable with respect to said port to regulate the flow of fluid therethrough, said valve member having a flow restricting passage through which fluid flowing through said port and into said valve member passes to build up a back pressure tending to elevate said valve member to restrict fluid flow through said port; said valve member being movable downwardly in said tubular means to a position closing said port; and means for securing said valve member in said port closing position.

4. In well apparatus: tubular means adapted to be incorporated in a conduit string to be lowered in a well bore; a back pressure valve in said tubular means adapted to close in an upward direction; said tubular means having a port through its side wall above said back pressure valve; a valve member in said tubular means having a passage therethrough in fluid communication with said back pressure valve and movable with respect to said port to regulate the flow of fluid therethrough, said valve member having a flow restricting passage through which fluid flowing through said port and into said valve member passes to build up a back pressure tending to shift said valve member in one longitudinal direction with respect to said tubular means to restrict fluid flow through said port; said valve member being movable in the other longitudinal direction to a position closing said port.

5. In well apparatus: tubular means adapted to be incorporated in a conduit string to be lowered in a well bore; a back pressure valve in said tubular means adapted to close in an upward direction; said tubular means having a port through its side wall above said back pressure valve; a valve member in said tubular means having a passage therethrough in fluid communication with said back pressure valve and movable with respect to said port to regulate the flow of fluid therethrough, said valve member having a flow restricting passage through which fluid flowing through said port and into said valve member passes to build up a back pressure tending to shift said valve member in one longitudinal direction with respect to said tubular means to restrict fluid flow through said port; said valve member being movable longitudinally in said tubular means in the other direction to a position closing said port; and means for securing said valve member in said port closing position.

6. In well apparatus: tubular means adapted to be incorporated in a conduit string to be lowered in a well bore; said tubular means having a port through its side wall; a valve member in said tubular means movable with respect to said port to regulate the flow of fluid therethrough, said valve member having an axial, central flow restricting passage through which fluid flowing through said port and into said valve member passes to build up a back pressure tending to move said valve member in one longitudinal direction within said tubular means to restrict fluid flow through said port; and means on said valve member for enabling said valve member to be shifted in the opposite longitudinal direction to a position closing said port.

7. In well apparatus: tubular means adapted to be incorporated in a conduit string to be lowered in a well bore; said tubular means having a port through its side wall; a valve member in said tubular means movable with respect to said port to regulate the flow of fluid therethrough, said valve member having an axial central flow restricting passage through which fluid flowing through said port and into said valve member passes to

build up a back pressure tending to move said valve member in one longitudinal direction within said tubular means to restrict fluid flow through said port; means on said valve member for enabling said valve member to be shifted in the opposite longitudinal direction to a position closing said port; and spring means acting on said valve member to urge it to a position allowing greater flow of fluid through said port.

8. In well apparatus: tubular means adapted to be incorporated in a conduit string to be lowered in a well bore; a back pressure valve in said tubular means adapted to close in an upward direction; said tubular means having a port through its side wall above said back pressure valve; a sleeve valve member in said tubular means having a passage therethrough in fluid communication with said back pressure valve and having a port adapted to be aligned with respect to said tubular means port to allow full flow of fluid through said ports, said sleeve valve member being shiftable to disalign said ports to restrict the flow of fluid therethrough, said sleeve valve member having a flow restricting passage through which fluid flowing through said ports and into said sleeve valve member passes to build up a back pressure tending to elevate said sleeve valve member to disalign said ports and restrict fluid flowing therethrough; said valve member being movable downwardly to a position closing said port.

9. In well apparatus: tubular means adapted to be incorporated in a conduit string to be lowered in a well bore; a back pressure valve in said tubular means adapted to close in an upward direction; said tubular means having a port through its side wall above said back pressure valve; a sleeve valve member in said tubular means having a passage therethrough in fluid communication with said back pressure valve and having a port adapted to be aligned with respect to said tubular means port to allow full flow of fluid through said ports, said sleeve valve member being shiftable to disalign said ports to restrict the flow of fluid therethrough, said sleeve valve member having a flow restricting passage through which fluid flowing through said ports and into said sleeve valve member passes to build up a back pressure tending to elevate said sleeve valve member to disalign said ports and restrict fluid flowing therethrough; releasable stop means in said tubular means engageable with said sleeve valve member to limit downward movement of said sleeve valve member and fully align said sleeve valve member port with said tubular means port; and means for releasing said stop means to enable said sleeve valve member to be shifted downwardly to a position closing said tubular means port.

10. In well apparatus: tubular means adapted to be incorporated in a conduit string to be lowered in a well bore; said tubular means having a port through its side wall; a sleeve valve member in said tubular means having a port adapted to be aligned with respect to said tubular means port to allow full flow of fluid through said ports, said sleeve valve member being shiftable to disalign said ports to restrict the flow of fluid therethrough, said sleeve valve member having an axial, central flow restricting passage through which fluid flowing through said ports and into said sleeve valve member passes to build up a back pressure tending to elevate said sleeve valve member from a position restricting fluid flow through said port to disalign said ports and restrict fluid flowing therethrough; and means on said sleeve valve member enabling said sleeve valve member to be shifted downwardly in said tubular means to a position closing said port in said tubular means.

11. In well apparatus: tubular means adapted to be incorporated in a conduit string to be lowered in a well bore; said tubular means having a port through its side wall; a sleeve valve member in said tubular means having a port adapted to be aligned with respect to said tubular means port to allow full flow of fluid through

said ports, said sleeve valve member being shiftable to disalign said ports to restrict the flow of fluid therethrough, said sleeve valve member having a flow restricting passage through which fluid flowing through said ports and into said sleeve valve member passes to build up a back pressure tending to elevate said sleeve valve member to disalign said ports and restrict fluid flowing therethrough; releasable stop means in said tubular means engageable with said sleeve valve member to limit downward movement of said sleeve valve member and fully align said sleeve valve member port with said tubular means port; and means for releasing said stop means to shift said sleeve valve member downwardly to a position closing said tubular means port.

12. In well apparatus: tubular means adapted to be incorporated in a conduit string to be lowered in a well bore; said tubular means having a port through its side wall; a valve member in said tubular means movable with respect to said port to regulate the flow of fluid therethrough, said valve member having a flow restricting passage through which fluid flowing through said port and into said valve member passes to build up a back pressure tending to move said valve member in one longitudinal direction within said tubular means to restrict fluid flow through said port; means on said valve member for enabling said valve member to be shifted in the opposite longitudinal direction to a position closing said port; and an elastic sleeve secured to said valve member and tubular means for urging said valve member from a position restricting fluid flow through said port to a position fully opening said port.

13. In well apparatus: tubular means adapted to be incorporated in a conduit string to be lowered in a well bore; a back pressure valve in said tubular means adapted to close in an upward direction; said tubular means having a port through its side wall above said back pressure valve; a shiftable valve member in said tubular means having a passage therethrough in fluid communication with said back pressure valve, said valve member having a port alignable with said port of the tubular means to permit fluid to flow through said port into said valve member and then upwardly into said tubular means and the conduit string; means for locating said valve member in said tubular means with said valve member port in alignment with said port of said tubular means; means within said valve member and responsive to the pressure of the fluid flowing through said ports for regulating the flow of fluid through said ports; and means for shifting said valve member downwardly in said tubular means to a position disaligning and closing said ports to prevent flow of fluid therethrough.

14. In well apparatus: tubular means adapted to be incorporated in a conduit string to be lowered in a well bore; a back pressure valve in said tubular means adapted to close in an upward direction; said tubular means having a port through its side wall above said back pressure valve; a shiftable valve member in said tubular means having a passage therethrough in fluid communication with said back pressure valve, said valve member having a port alignable with said port of the tubular means to permit fluid to flow through said port into said valve member and then upwardly into said tubular means and the conduit string; means for locating said valve member in said tubular means with said valve member port in alignment with said port of said tubular means; means within said valve member and responsive to the pressure of the fluid flowing through said ports for regulating the flow of fluid through said ports; means for shifting said valve member downwardly in said tubular means to a position disaligning and closing said ports to prevent flow of fluid therethrough; and means for securing said valve member in said port closing position.

15. In well apparatus: tubular means adapted to be incorporated in a conduit string to be lowered in a well bore; a back pressure valve in said tubular means adapt-

ed to close in an upward direction; said tubular means having a port through its side wall above said back pressure valve; a shiftable valve member in said tubular means having a passage therethrough in fluid communication with said back pressure valve, said valve member having a port alignable with said port of the tubular means to permit fluid to flow through said port into said valve member and then upwardly into said tubular means and the conduit string; means within said valve member and responsive to the pressure of the fluid flowing through said ports for regulating the flow of fluid through said ports; releasable means for preventing downward movement of said valve member to a position disaligning said ports; and means for shifting said valve member downwardly in said tubular means to release said releasable means and then locate said valve member in a position disaligning and closing said ports to prevent flow of fluid therethrough.

16. In well apparatus: tubular means adapted to be incorporated in a conduit string to be lowered in a well bore; a back pressure valve in said tubular means adapted to close in an upward direction; said tubular means having a port through its side wall above said back pressure valve; a shiftable valve member in said tubular means having a passage therethrough in fluid communication with said back pressure valve, said valve member having a port alignable with said port of the tubular means to permit fluid to flow through said port into said valve member and then upwardly into said tubular means and the conduit string; means within said valve member and responsive to the pressure of the fluid flowing through said ports for regulating the flow of fluid through said ports; releasable means for preventing downward movement of said valve member to a position disaligning said ports; means for shifting said valve member downwardly in said tubular means to release said releasable means and then locate said valve member in a position disaligning and closing said ports to prevent flow of fluid therethrough; and means for securing said valve member in such port closing position.

17. In well apparatus: tubular means adapted to be incorporated in a conduit string to be lowered in a well bore, said tubular means having a port through its side wall; a shiftable valve member in said tubular means having a passage therethrough and also having a port alignable with said port of the tubular means to permit fluid to flow through said ports into said valve member and then upwardly into said tubular means and the conduit string; means for locating said valve member in said tubular means with said valve member port in alignment with said port of said tubular means; means within said valve member and responsive to the pressure of the fluid flowing through said ports for regulating the flow of fluid through said ports; and means for shifting said valve member downwardly in said tubular means to a position disaligning and closing said ports to prevent flow of fluid therethrough.

18. In well apparatus: tubular means adapted to be incorporated in a conduit string to be lowered in a well bore, said tubular means having a port through its side wall; a shiftable valve member in said tubular means having a passage therethrough and also having a port alignable with said port of the tubular means to permit

fluid to flow through said ports into said valve member and then upwardly into said tubular means and the conduit string; means for locating said valve member in said tubular means with said valve member port in alignment with said port of said tubular means; means within said valve member and responsive to the pressure of the fluid flowing through said ports for regulating the flow of fluid through said ports; means for shifting said valve member downwardly in said tubular means to a position disaligning and closing said ports to prevent flow of fluid therethrough; and means for securing said valve member in such port closing position.

19. In well apparatus: tubular means adapted to be incorporated in a conduit string to be lowered in a well bore, said tubular means having a port through its side wall; a shiftable valve member in said tubular means having a passage therethrough and also having a port alignable with said port of the tubular means to permit fluid to flow through said ports into said valve member and then upwardly into said tubular means and the conduit string; means within said valve member and responsive to the pressure of the fluid flowing through said ports for regulating the flow of fluid through said ports; releasable means for preventing downward movement of said valve member to a position disaligning the ports; and means for shifting said valve member downwardly in said tubular means to release said releasable means and locate said valve member in a position in which said ports are disaligned and closed to prevent flow of fluid therethrough.

20. In well apparatus: tubular means adapted to be incorporated in a conduit string to be lowered in a well bore, said tubular means having a port through its side wall; a shiftable valve member in said tubular means having a passage therethrough and also having a port alignable with said port of the tubular means to permit fluid to flow through said ports into said valve member and then upwardly into said tubular means and the conduit string; means within said valve member and responsive to the pressure of the fluid flowing through said ports for regulating the flow of fluid through said ports; releasable means for preventing downward movement of said valve member to a position disaligning the ports; means for shifting said valve member downwardly in said tubular means to release said releasable means and locate said valve member in a position in which said ports are disaligned and closed to prevent flow of fluid therethrough; and means for securing said valve member in such port closing position.
